GRADUATED UNIVERSAL VALVE FOR GAS
APPLIANCES WITH PORTED SLEEVE

Isaac Vernon Brumbaugh, Clayton, Mo.

Application February 6, 1948, Serial No. 6,719

6 Claims. (Cl. 137—637)

1

The invention described in this application relates to valves. The valve disclosed and described herein in illustration of the invention is especially designed for use in controlling a cooking top burner of a kitchen range but it is to be understood that the inventions involved clearly have other uses. Thus the inventions involved are also useful in the control of gas oven burners. They may be used for control of gas outside of the cooking field. They may even be used for the control of other fluids.

The valve illustrated is designed so that not only may the gas be turned on and off but also the size of the flame may be varied as the valve is rotated from the "on" position to the "off" position or from the "off" position to the "on" position or from the "on" position to the "simmer" position, etc. For example as illustrated—the size of the gas flame may be decreased in a uniform gradual manner from an "on" or maximum flow position down to a condition in which the flame will provide only enough heat to cause the material being cooked to boil gently or simmer and then to the closed or "off" position. On the other hand if desired I may of course modify the design in an obvious manner to provide similar valves in which the valve may be turned from the "off" position directly to the "on" position and then turned gradually from the "on" position decreasing gradually through an infinite number of positions to the "simmer" position.

Prior hereto the large majority of gas valves (especially valves for controlling the cooking top burners of gas ranges) have been produced with a single port which may be opened or closed so that in the open position there is substantially a full flow of gas and in the closed position there is no flow of gas. As the ports are brought from exact registration to the closed position there is a decrease in the size of the flames produced with such prior art valves but inasmuch as the control is not usually accurate nor definite with such prior art valves, the operator has to be very careful to prevent turning the gas completely off or to such a low position that the flame will go out. In order to obviate this difficulty designers have designed valves with a plurality of different sized ports through which gas may flow. These are usually complicated and expensive to manufacture and some are very difficult to control.

My inventions are especially important where used in connection with a gas having a high heating value (i. e. high B. t. u. rating) such as the liquid petroleum gases (e. g. butane and propane), and also the natural gases. With such

2

gases it is especially difficult with a single port to obtain a simmer flame without inadvertently extinguishing the flame entirely. The prior art valves heretofore referred to, which are formed with a plurality of ports, are not always satisfactory with all types of gases because of their wide range in heating values, specific gravities and distribution pressures. The table given in my co-pending application, Serial No. 776,687, filed September 29, 1947, gives the approximate statistics for various types of gas and illustrates the wide differences in these important characteristics thereof. Not only the B. t. u. value of the gas, but also the specific gravity thereof and the distribution pressure under which the gas is supplied, affect the adjustment of the valve. Wherever used hereafter in this specification and claims I intend the words "heating value" or "heat value" to be construed to mean heating value, specific gravity of gas and/or distribution pressure thereof, etc.

Another disadvantage of the prior art valves employing a plurality of ports is that rotation of the valve produces a series of flames of different sizes by steps while by the operation of my valve disclosed herein I may produce a slowly varying gradual uniform turn down flame.

In the valve described and shown in this application in illustration of my invention, instead of providing a plurality of ports each controlled by a separate valve member I provide a valve plug with a tapered port and a cup like sleeve which has a relatively large opening and also a gradually tapering slot. This sleeve and the plug may be rotated relative to each other so that either the relatively large opening or portions of the tapered slot will register with the tapered port of the plug valve. Thus gas may flow through the port of the plug valve and then depending on the setting of the valve either through a selected portion of the tapered slot or the large opening of the sleeve into the interior of the sleeve and thence to the burner. I provide means for rotating the plug valve so that different portions of the slot of the sleeve register with the port thereof and so that the amount of gas supplied to the burner may be infinitely varied. I also provide means by which the longitudinal position of the sleeve may be varied relative to the plug valve so that the "simmer" position flame and the other position flames may all be adjusted to compensate for gases of different heating values, specific gravities and distribution pressures. The means for changing the longitudinal position of the sleeve differs in the two

embodiments of my invention shown. In the one case an eccentrically threaded screw extending through the plug valve operates to push the cup like sleeve rearwardly against the compression of a spring. In the other a rod threaded concentrically through the plug operates to draw the cup like sleeve forward of the valve against the tension of a similar spring.

Objects

One of the objects of my invention therefore is the construction of an improved valve especially useful in connection with gas burners, the valve being simple in operation and economical of construction.

A further object of my invention is the provision of a valve especially useful in connection with gas burners which may be adjusted from a full "on" position through an infinite variation of positions to a "simmer" setting position or may be moved to an "off" position.

A further object of my invention is the provision in combination a valve of the character described of means for adjusting the valve to compensate for the different heating values of the gas for which it is to be used.

Features of my invention include the provision of a cup like sleeve which is adjustable longitudinally of a control plug for the valve in order to adjust for different heating values of the gas being supplied.

A further feature of my invention is the provision of a sleeve and a plug one of which is formed with a relatively large opening and also with a tapering slot which cooperates with the plug of the valve and the other of which is formed with a tapered port to provide an infinite variation of the amount of gas delivered thereby.

Further objects and features of the invention will be apparent from the subjoined specification and claims when considered in connection with the accompanying drawings illustrating two embodiments of my invention for the purpose of illustration only.

Drawings

In the drawings, Fig. 1 is a view in side elevation of a valve constructed according to my invention;

Figure 2 is a view on an enlarged scale and in vertical section of the valve illustrated in Fig. 1 showing the valve associated with a mixing tube of a gas burner and with the front plate of a gas range;

Fig. 3 is a fragmentary view taken substantially on the line 3—3 of Fig. 2 having portions of the casing broken away and illustrating the cooperation of the tapered port in the plug with the tapered slot of the sleeve;

Fig. 4 is a view in front elevation of the valve of Fig. 1 showing also a fragment of the range; Fig. 5 is a view in end elevation of the valve of Fig. 1, the control knob having been removed;

Fig. 6 is a view in elevation of the sleeve when removed from the valve;

Fig. 7 is a view in vertical section taken substantially on the line 7—7 of Fig. 1;

Fig. 8 is a view in vertical section taken substantially on the line 8—8 of Fig. 1;

Fig. 9 is a view as if in a vertical section corresponding substantially to Fig. 2 but showing a different embodiment of my invention;

Fig. 10 is a view as if in an end elevation corresponding substantially to Fig. 5 but showing the end elevation view of the valve of Fig. 9 with the control knob removed; and

Fig. 11 is a view in vertical section of the valve of Figs. 9 and 10 taken as if substantially on the line 11—11 of Fig. 9.

Detailed description

Referring now to the drawings for a detailed description of my invention it may be seen that I have shown a gas cock 61 having a main casing 62 and a supplementary cover 63. Formed on the rearward end of the casing 62 is a threaded projection or nozzle 64 onto which there may be screwed (as is shown in Fig. 2) an orifice cap 65. The casing 62 is also formed with a downwardly extending threaded boss 66 which is adapted to be threaded into a gas manifold. The orifice cap 65 is adapted to be extended into the end of a mixing tube 68 (Fig. 2). Positioned in the casing 62 is a tapered valve plug 70 having a central recess 71 formed in the rear end thereof and having a forwardly extending stem 72 onto which there is secured a knob or operating dial 73. The valve plug 70 is formed with an oblique threaded bore inclined to the axis of the plug. Threaded into this inclined bore is an adjustment screw 74 bearing at its rearward end on a washer 74a which in turn bears on a sleeve 75 which is positioned in the recess 71. The sleeve 75 surrounds a spring retaining screw 76 which is screwed concentrically into a central bore formed in the plug 70. Surrounding the screw 76 is a spring 77 which bears at its rearward end on the head 76a of the screw 76 and at its forward end on a washer 76b fitted against the inner side of the base of the cup like sleeve 75. Thus the sleeve 75 is resiliently held by the spring 77 against washer 74a bearing against the inner end of the screw 74 and thus by means of the screw 74 the position of the sleeve 75 may be adjusted longitudinally of the plug 70. The washers 74a and 76b preferably are hardened. They as well as the sleeve 75 should be thoroughly and efficiently lubricated.

Referring for the instant to Figure 3 it may be seen that the plug 70 is formed with a groove 78 which extends more than half way around the circumference of the plug. It is also formed (see Fig. 3) with a tapered port or opening 79 by which gas flowing through the groove 78 may pass into contact with the exterior of the sleeve 75. The sleeve 75 is formed with both a relatively large opening 81 and with a tapered slot 82. The threaded projection 66 is formed with an inlet bore 80. Thus (assuming that the plug 70 has been turned to such a position that a portion of the groove 78 registers with the inlet bore 80) it is obvious that the size of the opening through which gas may flow from the groove 78 into the interior of the sleeve 75 is determined by the relative position of the sleeve 75 to the plug 70. As stated previously the plug 70 may be rotated by means of the knob 73. It is obvious also that opening 81 and the tapered slot 82 may be formed in the plug 70 while the tapered port 79 may be formed in the sleeve 75.

However, means are provided to hold the sleeve 75 against rotation. Referring especially to Figs. 2 and 7 it may be seen that the sleeve 75 is formed with a relatively small projection 83 and with a relatively large projection 84 which fit in corresponding grooves or slots 85 and 86 which are formed in the interior surface of the casing 62.

Within the cover 63 there is provided a stop sleeve 87 having a stop 88 (Fig. 5) which cooperates with a stop 89 formed on the cover 63 to prevent turning the operating dial 73 clock-

wise farther than the "off" position or counter clockwise farther than the "on" position. A spring 90 bearing at its forward end on the sleeve 87 maintains the plug 70 in the casing 62. The casing 63 is also formed with a cut out portion or opening 91 through which access may be obtained for the purpose of adjusting the screw 74 as desired. It is to be noted in this connection that the opening 91 is arranged in such position that the screw is in position for adjustment through the slot 91 when and only when the plug 70 and the sleeve 75 cooperate to allow a minimum flow of gas (i. e. the simmer set position).

Relatively large screw 92 and relatively small screw 93 are provided to hold the cover 63 to the main casing 62; the screws being of different size so that improper assembly is impossible.

As shown in Fig. 2 the valve may be assembled, if desired, with a range having a front plate 93. Primary air adjustment in the mixing tube 68 may be obtained by the adjustment of a plate 94 adjustably secured to the mixing tube 68 by means of a screw 95.

In Figures 9, 10 and 11 another valve illustrating my invention is shown. Therein the casing 162 is joined to the cover 163 and has a tapered bore into which the tapered plug 170 extends. It is provided with an inlet boss 166. The nozzle 164 is provided with an orifice cap 165 which extends into a mixing tube 168. In the central recess 171 is a sleeve 175. Onto the forwardly extending stem 172 is an operating knob 173. Threaded concentrically through the stem 172 and through the sleeve 175 is an adjusting screw 174 on the rear end of which is a nut 176 which bears on a hardened washer 176b in turn bearing on the base of the sleeve 175. Surrounding the screw 174 within the recess 171 is a spring 177 which bears on a hardened washer 174a and maintains the sleeve 175 in contact with the washer 176b in turn bearing on the nut 176. A spring 190 bears on the plug 170 and on the stop sleeve 187. The projection 188 on the stop sleeve 187 cooperates with stop 189 to limit rotation of the plug. A tubular member 180 with a pair of keys 183 and 184 is press fitted into nozzle 164 so that the keys 183 and 184 fit into slots 185 and 186 formed in the end of the sleeve 175 and prevent rotation of the sleeve 175. Because of the difference in the size of the keys 183 and 184 they also prevent improper assembly.

Otherwise the sleeve 175 is like the sleeve 75 being formed with a large slot 181 and a tapered slot 182 which both cooperate with the tapered port 179 and the groove 178 formed in the plug 170.

Operation

The operation of the valves described above are as follows:

The valve 61 is installed with a range as shown in Fig. 2. The knob 73 is turned to the full "on" position. The orifice cap 65 is adjusted on the nozzle extension 64 to allow the passage of the proper amount of gas for the type of burner used (about 9000 B. t. u. per hour for a regular burner and 12,000 B. t. u. per hour for a giant burner). Then the air shutter 94 is adjusted on the mixing tube 68 to obtain the proper type of flame for most efficient operation. The knob 73 is then turned so that the indication "sim" (i. e. "simmer") is brought into registration with the pointer 96 (i. e. the position illustrated). This brings the screw 74 into registration with the

cut out portion 91. The knob is removed and the screw 74 is then adjusted to move the sleeve 75 longitudinally and to secure a correct simmer flame (i. e. about 1500 B. t. u. per hour for a regular burner and about 2000 B. t. u. per hour for a giant burner). This gives the exactly correct adjustments for both the full "on" position and the "simmer" position. The intermediate positions are thus automatically adjusted. It will be noted that an infinitely variable flame of any desired size may be obtained between "on" and "sim," it not being necessary to move to the exact positions 2, 3, 4, 5, 6, 7, and 8. These indications are helpful in adjusting the flame for cooking but obviously any desired number of intermediate positions could be indicated. Even if no intermediate numbered positions were indicated, the operation of the burner would be the same. In cooking operations, the valve is turned from the "off" position to any desired "on" position. It is to be especially noted that rotation of the knob 73 turns the plug 70 but does not turn the sleeve 75 which is held against rotation by the projections 83 and 84. Preferably it is turned to the position indicated "on." When the valve is in the "off" position (i. e. about 45° clockwise from the positions shown in Figs. 4 and 8) the groove 178 does not register with the bore 80. Thus no gas may flow from the bore 80 (which is connected with the inlet gas manifold) into the valve. If the valve plug is then turned counterclockwise to the "on" position, a full flow of gas flows from the manifold through the bore 80, the registering port 79 and large opening 81 into the interior of the sleeve 75 and thence through the nozzle 64, the orifice cap 65, the mixing tube 68 and to the burner. In this open position of the valve, the gas is automatically lighted, where flash tube lighting is provided, or it may be lighted in any other convenient manner. The valve may be left in such position to secure a maximum flame or may then be turned clockwise to the simmer "sim" position or to any intermediate position to secure any other desired flame. It should be noted that the size of the flame is infinitely variable between the simmer flame and the full flame. As the flame is turned down the supply of gas is restricted not only by the continuously smaller width of the slot 82 but also by the continuously smaller width (lengthwise of the slot 82) of the tapered portion of the port 79 (see Fig. 3).

In the valve shown in Figs. 9-11, the operation is the same except as follows: The position of sleeve 175 longitudinally of the plug 173 is adjusted (after the knob 173 is brought to the simmer position and removed), by rotation of the screw 174 during which operation and at all other times the sleeve 175 is held against rotation by the keys 183 and 184.

The embodiments of the valve disclosed herein are also disclosed and are claimed broadly in application Serial No. 66,710, filed December 22, 1948, which is intended to include claims generic to the inventions disclosed herein. Said application Serial No. 66,710 also discloses embodiments of my invention disclosed in my application Serial No. 776,687, filed September 29, 1946, and in my application Serial No. 27,167 filed May 15, 1948.

It is to be understood that the above described embodiments of my invention are for the purpose of illustration only and various changes may be made therein without departing from the spirit and scope of the invention.

I claim:

1. A valve comprising a hollow valve casing having an inlet port and an outlet port, a stationary member positioned in said hollow and a rotative member also positioned in said hollow and associated with the stationary member, the rotative member being formed with a tapered port and the stationary member being formed with an elongated sloping surface which at times lies contiguous to and cooperates with said port to effect a gradual adjustment of the flow of fluid through said valve, said stationary member and said rotative member comprising means for metering the amount of liquid flowing from said inlet port to said outlet port and said gradual adjustment of the flow being effected by the position of said tapering port relative to said elongated sloping surface.

2. A valve comprising a casing formed with an inlet port and an outlet port; a hollow rotatable plug fitted for rotation in said casing, formed with an external groove registering at times with said inlet port, and formed with a tapered port connected to said groove and extending through the wall of said plug from the hollow to the other circumferential surface thereof; and a hollow sleeve open at one end, positioned within the hollow of said plug, and formed with an elongated sloping slot extending through a wall of said sleeve and registering at times with said tapered port; and means for holding said sleeve against rotation so that rotation of said plug moves said tapered port and said slot into and out of registration.

3. A valve comprising a hollow casing formed with an inlet port and an outlet port; a hollow stationary valve member positioned in said casing and formed with a port extending through a side wall thereof; and a hollow rotative valve member associated with said stationary valve member and also formed with a port extending through a side wall thereof, and movable into and out of partial and full registration with the port in said stationary valve member, the port of the hollow rotative valve member having tapered arcual sides, and the port of the hollow stationary valve member comprising a slot having a sloping surface, which slot at times registers with, is contiguous to, and cooperates with the port in the hollow rotative valve member to effect a gradual adjustment of the flow of gas through said valve.

4. A valve comprising a hollow casing formed with an inlet port and an outlet port; a hollow stationary valve member positioned in said casing and formed with a port extending through a side wall thereof; a hollow rotative valve member associated with said stationary valve mem-

ber and also formed with a port extending through a side wall thereof, and movable into and out of partial and full registration with the port in said stationary valve member, the port of the hollow rotative valve member having tapered arcual sides, and the port of the hollow stationary valve member comprising a slot having a sloping surface, which slot at times registers and cooperates with the port in the hollow rotative valve member to effect a gradual adjustment of the flow of gas through said valve; and additional means for adjusting said valve members relative to each other along a line substantially parallel to the longitudinal axis of the rotative member.

5. A valve comprising a casing formed with an inlet opening and an outlet opening, a hollow rotatable plug positioned therein and formed with a concentric recess at its rearward end and with a full sized port extending from the circumferential surface thereof through the side wall to the recess, a hollow sleeve open at its rearward end positioned in said recess and formed with a slot with a sloping side and with a full sized oblong port extending through a side wall thereof non-restrictive to the flow of fluid and registering at times with the port in the plug and means for moving said ports into and out of registration.

6. A valve comprising a casing having an inlet and an outlet, a hollow tapered rotatable plug positioned therein and formed with a concentric bore and with a recess and formed with a port extending through a side wall thereof from the outer circumferential surface to said recess, a sleeve positioned in said recess and formed with a port extending through a wall thereof and moving at times into and out of partial and full registration with the port in said plug, a spring resiliently urging said sleeve longitudinally of said recess and means, comprising a screw threaded through said bore and bearing on said sleeve, for moving said sleeve longitudinally against the urging of said spring.

ISAAC VERNON BRUMBAUGH.
